United States Patent

Des. 239,899
Patented May 18, 1976

239,899

MUSIC STAND

Frederick H. Malcolm, 2950 NE. 23rd St.,
Gresham, Oreg. 97030

Filed Oct. 31, 1974, Ser. No. 519,532

Term of patent 14 years

Int. Cl. D6—99

U.S. Cl. D6—18

FIG. 1

FIG. 2

FIG. 3

FIG. 4

FIG. 5

FIG. 1 is a side elevation view of a music stand in accordance with my new design;

FIG. 2 is a front elevation view thereof;

FIG. 3 is a top elevation view thereof;

FIG. 4 is a back elevation view thereof; and

FIG. 5 is a bottom elevation view thereof.

I claim:

The ornamental design for a music stand, as shown.
